UNITED STATES PATENT OFFICE.

AUGUST ABEL, OF LEIPZIG, GERMANY, ASSIGNOR TO ATLAS-WERKE PÖHLER & CO., OF LEIPZIG-STOTTERITZ, GERMANY.

FOOTWEAR POUNDING OR BURNISHING MACHINE.

Application filed April 23, 1926, Serial No. 104,241, and in Germany May 27, 1925.

This invention relates to footwear pounding or burnishing machines, and more particularly to the pounding heads or drums of such machines, in which a number of 5 pounding elements are loosely and turnably mounted upon rods extending between two ends plates.

The main object of the invention is to provide a pounding drum with which it will 10 be possible to pound or burnish boots and shoes at such places where the hitherto usual means failed to reach the leather as, for example, the cavities of strongly arched 15 footwear, and similar places.

15 A further object is the general improved construction and arrangement of the drum and its pounding elements as will be fully set forth.

With these and other objects in view the 20 invention mainly consists in providing the drum, in addition to its usual arrangement of elements between the two end plates, with further pounding elements outside the said 25 end plates. These external elements are mounted on freely extending pins so that they are able better to reach into any cavities such as a lasted shoe or boot may present.

In the accompanying drawings several 30 ways of carrying out the invention are illustrated by way of example.

Fig. 1 illustrates a pounding head of the hitherto usual type in position for pounding the arch of a shoe.

Fig. 2 is a similar view of a pounding 35 head according to the invention.

Fig. 3 is a side elevation thereof; half 40 of the figure only being shown.

Fig. 4 illustrates a modified form of the 45 invention.

Fig. 5 represents a simplified form of construction.

For the sake of clearness all front views 50 are shown with the top and bottom lines of pounding elements only.

First of all the mode of operation of the 55 known devices may be explained; reference being had to Fig. 1 of the drawings. In this figure, 1 is the working shaft to which the end plates or carriers 2, 2^a are rigidly connected. These end plates carry a number of 60 rods 3 between them, which are spaced all around the circumference at a short distance therefrom. The said rods 3 carry the pounding element which, in all the examples 65 shown, consist of rollers 4. When working

on a shoe or boot having a strongly expressed arch such as indicated at *x* in Figs. 1 and 2, it is evident that the rollers 4 will not be able to reach all parts of the cavity. As a matter of fact, it is usually only the 60 ball portion of the shoe with which the rollers are able to contact, as indicated at 4^a, (Fig. 1) whilst the heel portion can not be reached by the rollers owing to its interfering with the end plates as at 2^b (Fig. 1). 65 The rollers 4^b of Fig. 1 are therefore unable to contact and work upon the material at that place. Now, in order somewhat to alleviate this disadvantage it has been proposed to mount the rods as close as possible to the 70 circumference of the end plates 2 and 2^a, to cause the rollers to project further beyond the end plates. However, in view of the considerable centrifugal forces set up by the 75 high rotary speed of the drum, the rods cannot be placed so near the circumference as to remove the said drawback.

In the arrangement according to the invention as shown in Fig. 2, the rollers 4 are arranged upon the rods 3 not only between 80 the two end plates 2 and 2^a as in the above example, but also so as to extend from their outer faces as shown at 4^c. Like the rollers 4 between said plates, the rollers 4^c may be concentric or eccentric, or in the shape of 85 rings, rollers or discs, or they may be club-shaped or of any other convenient form or size. Their arrangement upon the rods 3 is both simple and effective. As will be apparent from Fig. 2 the elements 4^c outside 90 the end plates can be brought to bear upon even the deepest places of the cavity without their action being in the least interfered with by the discs 2 and 2^a.

It is advisable to provide fixing means for 95 the axially protruding rollers 4^c, such as pin heads 6 for example, in such manner as to preclude their hindering the action of the rollers in any way. For this reason the heads of the fixing screws or pins 6 may be 100 made comparatively flat, or they may be countersunk into the last ring or roller of each line. It is also advisable to round off the edges of the outermost rollers as indicated at 7, in order to prevent the leather 105 of the boots or shoes under treatment becoming scratched or otherwise damaged. Besides, the rollers, when rounded off in this way, will snugly fit the shanks of the shoes and thus be most effective in their action. 110

In Figs. 2 and 3 of the drawings the elements 4 and 4^c are arranged upon the same rods 3 extending at both sides through the end plates 2 and 2^a. Said rods 3 are secured against turning by plate sectors 8 which project into slots or recesses 9 cut therein, whereas the sectors themselves are retained upon the end plates 2, 2^a by means of screws 10 passing through slots 11 in the said sector plates, so as to be adjustable.

Fig. 4 shows a modified arrangement of the pounding elements in that the rollers 4 are positioned upon rods 12 extending between the end plates 2, 2^a in the usual manner, while the external rollers 4^c are mounted on short studs or pins 13 externally fixed in said end plates in alternating succession with the said rods 12. According to the sense of rotation it is advisable to use right hand threaded screws or bolts at one side of the drum, and left hand threaded screws or bolts at the other side. In this way no special locking means need be employed.

The same advantageous results as mentioned above can be obtained with the construction shown in Fig. 5. In this case, however, only one carrier plate 14 is provided instead of the two end plates 2 and 2^a, and the elements 4^c are arranged on pins 15 passing through the said plate so as to project therefrom at both sides.

It will be readily understood that in addition to the usual way of applying the work to the front of the drum, the invention admits of the workpiece being moved cornerways around the edges of the drum where it will also be hit by pounding elements without the risk of contacting with portions of the body or frame of the drum. Thus any grinding, tearing or otherwise undesirable effects upon the workpiece are effectually avoided.

What I claim is:—

1. In a pounding drum for footwear pounding machines, a rotary carrier having loosely arranged pounding elements extending freely from the outer faces of said drum on opposite sides thereof.

2. In a pounding drum for footwear pounding machines, the provision of pounding elements mounted to extend freely beyond the outer faces of the drum.

3. In a pounding drum for footwear pounding machines embodying end-plates and pounding elements, the provision of

pounding elements at the outside of the end plates in addition to elements mounted between the said end plates.

4. A pounding drum having in combination a rotary member, pins extending from the outer faces of the said member in axial direction, and pounding elements mounted upon the said pins.

5. A pounding drum having in combination a rotary member, pins extended freely from the outer faces of the said member in axial direction, pounding elements mounted upon the said pins, and rounded holding means at the ends of the said pins.

6. A pounding drum comprising two end plates, rods extending between the said end plates circumferentially thereof, pounding elements loosely and turnably mounted upon the said rods, pins extending from the outer faces of the said end plates, further pounding elements mounted upon these pins, and rounded heads to the said pins to retain the pounding elements in position.

7. In a pounding drum for footwear pounding machines the arrangement of pounding elements upon rods arranged circumferentially between revoluble carrying plates, and of pounding elements similarly arranged on flying pins at the outer faces of the said carrying plates, said rods and the said flying pins being arranged in alternating succession around the circumference of the carrying plates.

8. A pounding drum having in combination a rotary member, pins freely extending from the outer faces of the said member in axial direction, pounding elements mounted on the said pins, slots in the pins adjacent the outer faces of the rotary member, and ring segments to engage the said slots and thus lock the said pins in position.

9. A pounding drum having in combination a rotary member, pins freely extending from the outer faces of the said member in axial direction, pounding elements mounted on the said pins, slots in the pins adjacent the outer faces of the rotary member, ring segments engaging the said slots to lock the pins in position, slots in the said ring segments, and screws passing through the said slots adjustably to secure the said ring segments upon the outer faces of the rotary member.

In testimony whereof I affix my signature.

AUGUST ABEL.
